ROUNDING MACHINE

John M. Whelton, Peabody, Mass., assignor to
United Shoe Machinery Corporation, Borough
of Flemington, N. J., a corporation of New
Jersey

Application December 22, 1938, Serial No. 247,239

30 Claims. (Cl. 12—88)

My invention relates to machines by which there is imparted to work-pieces a peripheral contour which at least approximates the finished form. It is especially applicable to the rounding of soles which have been attached to shoes.

In the rough-rounding of shoe-soles, there may be about portions of the margins considerable widths of material to be trimmed away. In some types of shoes, as stitchdowns, the difficulty is increased by the presence in the margin of other than sole-material, such as the flange of the toe-box and the lining. It is an object of the present invention to effect such rounding operations rapidly and accurately and with relatively little effort on the part of the operator and wear of the cutting means. In achieving this object, I preferably employ a rotatable cutter, together with means arranged to engage a shoe-upper at points along the crease opposite the margin of an attached sole and spaced from said upper outside the crease, this means being adapted to guide such a work-piece as a shoe-sole in a direction generally parallel to the axis of the cutter, with the sole presented to said cutter to be severed along an edge-surface substantially at right-angles to the opposite faces of the sole. Herein, the cutter is shown as having spaced arms provided with peripheral cutting edges entering the margin of the sole at the side toward the shoe-upper and an associated cutting edge extending inwardly from each peripheral edge. Both of these cutting edges may co-operate with stationary shear-blades, which are preferably variable in position independently with respect to the cutter. With this arrangement, the sole-margin is severed between its opposite faces along the desired edge-surface by successive cuts, each requiring the application of but little power and permitting the work to be advanced easily and rapidly, the intermittance of the cutting action giving intervals during which the forward feed is accomplished without meeting material resistance. The inwardly extending cutting edges cause the production of relatively small waste-pieces, which are readily disposed of without interference with the manipulation of the work, and the co-operation of the stationary blades insures clean lines of division. Guiding means for the shoe may comprise a member arranged to enter the crease, and because of irregularities in the crease at the forepart of work of some characters, there is preferably also an upper-guide, either of which guides may be made effective. To allow for proper operation upon work of different thick-

nesses, both guides are yieldable. In the illustrative machine, one of the guides is carried by and arranged to move into and out of its active position upon the other, which is itself movable. 5 The guides may thus yield together, regardless of the one in use. I have shown the crease-guide carried for this movement upon a lever and the upper-guide as sliding upon the crease-guide and actuated by connections which are without effect upon the movement of the crease-guide. To provide for easy access to the cutting elements, the guide or guides are best mounted upon a carrier, variable in position upon a controlling lever and being arranged to be secured in active and inactive positions. The operator may be assisted in advancing the work for the operation upon it by a rotatable feeding member, engaging the sole at the opposite side from that against which the cutter moves. I prefer this feeding member to be in the form of a belt. Such a member is relatively inexpensive and provides an effective, yieldable contact-surface, which will give long service because of its considerable extent and which, when worn, is readily renewable. By mounting one of the belt-pulleys or other feeding member which is adjacent to the cutting mechanism upon a tubular shaft, a support for a shear-blade may extend through it, giving a convenient, compact arrangement. A rest for the bottom of the sole is illustrated, this being below the feed-belt. It is adjustable to vary its position inwardly or outwardly with respect to the work-engaging surface of said belt. This provides for the presentation of the sole-edge at different angles to the peripheral portion of the cutter.

In the accompanying drawings, a particular embodiment of the invention is illustrated,

Fig. 1 showing the more essential portions 40 of the machine in side elevation;

Fig. 2 being an enlarged top plan view of the operating elements, with parts omitted;

Fig. 3, a side elevation of these elements;

Fig. 4, an enlarged broken elevation from the side opposite that of Fig. 3 and including elements more closely associated with the work;

Fig. 5, a front elevation generally corresponding to Fig. 3;

Fig. 6, a top plan view of the machine with the upper section of the frame-head removed but with the elements of the cutting mechanism indicated;

Fig. 7, a fragmentary plan view specially illustrating the block carrying the vertical shear-

blade and the manner in which the block and blade are adjusted;

Fig. 8, a fragmentary elevation showing the position of the crease-gage and the upper-gage, elevated from their operating positions; and

Fig. 9, a view similar to Fig. 8, but showing the relation of the elements lowered, and with the upper-gage depressed into its active relation.

The machine has a column 10, upon which is mounted a frame-head 12, having an upper section 13. Journaled transversely in a bearing secured to the head 12 at the front of the section 13 is a shaft 14, upon which is secured a cutter C. This cutter has arms 16 radiating from its hub, these being shown as two in number and spaced from each other by 180°. Each blade has a peripheral cutting edge 18, which may be parallel to the axis of rotation and extending inwardly from which is a cutting edge 20 (Fig. 4). These cutting edges are preferably formed upon inserts 22 of some very hard material, of which Carboly furnishes an example, attached to the cutter-arms, as by soldering. Each of the revolving cutter-edges has co-operating with it a fixed shear-blade. Each edge 18 travels close to the horizontal forward edge 24 (Fig. 5) of a plate or blade 26 mounted for vertical adjustment toward and from the cutter, as will later be described. At one side of the plate 26 is a plate or blade 28, presenting a vertical shearing edge 30 to the edges 20 of the cutter. The plate 28 may be held in ways 32 upon a divided block 34 and clamped in place by a screw 36, which draws the divided portions toward each other. The block is pivoted at 38 (Figs. 3 and 7) upon a horizontal surface of the head-section 13 and is urged from the cutter by a spring 40 interposed between said block and the head-section and surrounding a screw 42 passing through an opening in the block. By turning the screw 42, the edge 30 may be adjusted toward and from the plane in which the cutter-edges 20 revolve. When the chosen relation is attained, the block, with the blades, may be secured in position by screws 44, extending with clearance through openings 46 in the block and threaded into the head. By adjustment of the shearing edges 24 and 30 with relation to the revolving cutter-edges, they may be caused to sever cleanly the material operated upon.

To present a shoe in such a relation to the cutter-edges and to the shear-blades that it will be trimmed an approximately uniform width along the margin to produce an edge which is substantially at right-angles to the opposite faces of the sole, a guide 50 is provided. At its lower extremity, this guide has a generally vertical portion 52, with a somewhat reduced extremity adapted to enter the crease of a shoe and lying opposite the shear-blocks, it diverging slightly therefrom horizontally in the direction of advance of the work, as appears in Fig. 4. This causes the cutter to operate in a plane at an angle somewhat removed from 90° with respect to the overhanging upper. It is therefore rendered less liable to strike said upper as the edges 18 approach the adjacent margin of the sole than if the advance were strictly parallel to the axis of the cutter. Above the portion 52, the guide is curved upwardly and outwardly to clear the cutter, as shown in Figs. 1, 3, 4, 8 and 9, and terminates in a shank 54 recessed into a carrier member 56 (Fig. 2), to which it is secured for vertical adjustment by a slot-and-screw connection 58. This permits a variation in the height at which the work is presented to the cutter-

edges 18 and therefore the width to which the sole-margin is trimmed. The carrier has projecting horizontally from it a spindle 60, which may turn in a bracket 62 attached to the head-section 13 (Figs. 3 and 5). Supported upon the end of the spindle is an actuating lever 64, which has inward projections 66, 68 above and below the bracket. In these projections are openings 68 and 70 (Fig. 4), either of which may be engaged by a spring-pin 72, mounted to move horizontally in the carrier 56. With the pin in the opening 68 (Fig. 9), the guide 50 is held down adjacent to the shear-blades in operating position. With the pin withdrawn from this opening, the carrier and guide may be swung up about the axis of the spindle 60, until the pin registers with the opening 70. Here, it may be released to hold the guide elevated and give access to the cutter C and the co-operating blades (Fig. 8). From the projections 66 and the intermediate hub 74, the lever 64 extends rearwardly and is articulated to a treadle-rod 76. A compression-spring 78 interposed between the end of the lever and the head-section 13 holds the crease-guide 50 normally in its active relation but allows it to yield to compensate for varying thicknesses of work passing between it and the shear-blades. When the rod 76 is drawn down, a clockwise movement of the lever 64 (Fig. 3) swings the guide away from the cutting mechanism, so the work may readily be placed in operating position.

With shoes in which the crease is reasonably smooth and uniform, as in the case of the stitch-down-form, in which an outward flange about the upper has been secured to an outsole or outsole-portion in lasting, the entire rounding operation may be performed under guidance of the portion 52. If, however, the work is of the pre-welt type, having a welt stitched to the upper before lasting, the crease about the forepart may have such irregularities that the use of the guide-portion 52 would result in a rounded sole-edge which would be objectionably uneven. I therefore associate with the crease-guide a guide 80, presenting at 82 a transversely curved surface with which the shoe-upper may contact. This guide 80 extends upwardly about the crease-guide 50, being correspondingly curved vertically and also concave transversely to partially surround and thus lie in proximity to said crease-guide. Since the upper-guide is to be used only in connection with certain kinds of work, and at particular portions thereof, it is held in a normally inactive, raised position, to be lowered to receive engagement of the shoe-upper when desired. For this purpose, it is preferably movable upon the crease-guide 50 and, consequently, moves therewith. It depends from a slide 84, which is guided upon vertical ways 86 at the outer side of the crease-guide. Fixed to the slide by a slot-and-screw connection 88 is a plate 90, to which a link 92 is pivoted at 94. The upper extremity of the link is joined at 96 to the downwardly extending arm of a bell-crank-lever 98, fulcrumed at 100 upon the carrier 56. A tension-spring 102, connecting the slide to the carrier between the points 94 and 100, maintains normally broken the toggle-lever furnished by the link and the lever-arm. This so elevates the surface 82 of the upper-guide that the guide-portion 52 is exposed to enter the crease of a shoe, as appears in Fig. 3. To lower the upper-guide, a rearwardly extending arm of the bell-crank-lever 98 carries a roll 104. Above this roll

extends a surface 106 upon a lever 108, fulcrumed at 107 upon the head-section 13 and having pivotally joined to it a treadle-rod 109. A compression-spring 113 located about the rod and between the lever 108 and the head-section, holds both the rod and lever normally raised. When the lever is swung down upon depression of the rod 109, the surface 106 bears upon the roll 104 and turns the bell-crank-lever 98 to more nearly straighten the toggle. This lowers the slide 84 and the guide 80, until the surface 82 is below the portion 52 of the crease-guide. The latter is now ineffective, and the guiding action is transferred to the engagement between the shoe-upper and the guide-surface 82. It is to be noted that when the crease-guide 50 is raised by the treadle-rod 76 for the reception of the work, the upper-guide moves with it, remaining in its inactive position upon the crease-guide. When the crease-guide swings up with its carrier 56 to free the cutting mechanism, the upper-guide similarly shifts with it. Moreover, this movement of the crease-guide is in no way interfered with by the action of the treadle-rod 109 in lowering the upper-guide, since the roll 104 upon the bell-crank-lever 98 at this time does not approach the contact-surface 106 of the lever 108, the two being free to travel into and out of effective relation. The connection of the link 92 to the adjustable plate 90 allows the normal position of the upper-guide to be varied independently of the crease-guide. By this means, in connection with the adjustment of the crease-guide at 58, width of the trimmed margin over both the shank and forepart may be determined separately.

To aid the operator in advancing a shoe to receive the action of the cutter C, there preferably contacts with the shoe-sole a rotatable feeding member. This is shown as an endless belt 110, which may be of the V-type, running horizontally over a pulley 112 at the front of the machine and a pulley 114 at the rear (Fig. 6). The vertical surface 116 of the belt (Fig. 3), which engages the sole, is of some such material as rubber, giving the desired tractive force and avoiding marring the work. The pulley 112 has a tubular shaft 118 journaled in the head 12, and advantage is taken of the passage through the shaft to position, without interference, the horizontal shear-plate 26. This plate is secured to a cylindrical carrier 120 (Fig. 5) movable vertically in the shaft-bore. From it is a downward extension 122, guided upon the head. From the extension depends a rod 124, threaded at its lower extremity and passing freely through an opening in a projection 126 from the head. Upon the rod at opposite sides of the projection are nuts 128. By these nuts, the plate 26 may be raised or lowered to bring it into correct shearing relation to the edges 18 of the cutter.

To insure the maintenance of the sole-edge in the correct angular relation to the edges 18 of the cutter, a bottom-rest may be mounted upon the head 12 just below that portion of the feed-belt 110 which engages the sole of the shoe being operated upon. The rest has a horizontal arm 129, with an outwardly curved surface 131 to receive contact of the sole. It is secured to the head by a slot-and-screw connection 133. Because of the angle at which the rest is attached to the head, its longitudinal adjustment causes the contact-surface 131 to occupy different horizontal positions inwardly or outwardly with respect to the surface 116 of the feed-belt. With this adjustment, the angle of the sole-edge may

be varied with respect to the arc through which the cutter-edges 118 revolve, and thus the trimmed edge may be kept more nearly at right-angles to the opposite faces of the sole as the thickness of said sole varies in different work.

The chips and dust produced by the cutting operation may be removed through a conduit 130 (Fig. 1), the intake-opening of which is adjacent to the rear of the cutter, and the opposite end of which connects with the eye of a suction-fan contained in a casing 132. The waste from the outlet of the fan is deposited in a container 134, removably clamped in ways 136 in a bracket 138 secured to the frame-column 10. The waste is confined to a largely enclosed space about the operating elements, the enclosure being furnished by a hood 131 pivoted upon the section 13 of the head. The hood also protects the operating elements and may be thrown back to give access to them.

The rotatable elements of the machine are driven from a counter-shaft 140 (Figs. 1 and 6), journaled transversely at the rear of the head 12 and receiving power from line-shafting through fast and loose pulleys 142 and 144, respectively, or from an electric motor. In the former case, the belt to these pulleys may be shifted by a lever 146. When power is off, rotation may promptly be checked by brake mechanism 148 associated with the shaft 140. Upon said shaft is shown in Fig. 6 a pulley having a groove 150, which may be connected by a belt 152 to the motor, when this is used; a groove 154, having a belt 156 to the fan-shaft; and a groove 158, joined by a belt 160 to a pulley 162 turning about an intermediate spindle 164 projecting from a bracket 165 secured to the head. With the pulley 162 rotates a pulley 166, over which and over a pulley 168 upon the cutter-shaft operates a belt 170. By this belt-gearing to the pulley 168, the rotation of the cutter-shaft is stepped up to the desired high speed. The opposite extremity of the counter-shaft 140 from its pulleys 150, 154 and 158, is united by worm-gearing 172 to a vertical shaft 174, rotatable in bearings in the head and upon which is the pulley 114 for the feed-belt 110. The travel of this belt is thereby reduced to a relatively low speed.

To facilitate an operation which may follow that of rounding, as outsole-stitching, oil or the like may be supplied, drop by drop, from a drip-cup 180 (Fig. 1) mounted upon the top of the head-section 13. A pipe 182 unites the cup to a valve 184 for controlling the flow, which is received by a tray 186 and delivered through a pipe 188, terminating just above the crease of the shoe being operated upon, adjacent to the cutter.

In rounding a sole which, in a stitchdown, will have been temporarily secured to the outwardly turned flange of its upper or to a welt preattached to said upper, the operator depresses the rod 76, thereby turning the lever 64 to carry away from the shear-blades 26 and 28 the portion 52 of the crease-guide 50 and, with it, the upper-guide 80, supported by the crease-guide. In this movement, the roll 104 upon the bell-crank-lever 98, controlling the upper-guide, moves away from the surface 106 of the lever 108, so the relative movement affects neither guide. Since the upper-guide is so raised by the link 92 that its gaging surface 82 is above the guide-portion 52, the operator finds the latter free, so he may apply to it the crease of the shoe. Upon releasing the rod 76, the crease-

guide and the shoe are carried down by the spring 78, until the tread-surface of the sole rests against the vertical faces of the shear-blades, the surface 116 of the feed-belt 110 and, if the operator chooses to utilize it, the bottom-rest 129. The cutter C and the feed-belt being in constant rotation, as the operator advances a shoe, aided by the belt, and turns said shoe, which is held by the crease-guide in a definite vertical position opposite the cutter, one of the peripheral cutting edges 18 descends past the upper and severs a short section of the sole-margin. As it operates over the shearing edge 24 of the plate 26, it produces a clean cut, which is substantially at right-angles to the opposite faces of the sole. While the movement of the work is generally parallel to the axis of the cutter, it may be held at a slight angle, as indicated in Fig. 6, so said cutter more certainly clears the upper, especially where it considerably overhangs the sole, as at the shank. Following the engagement of the cutter-edge 18 with the sole, the inwardly extending edge 20 cuts through the sole-margin, and as long as the length of its edge 20 exceeds the width of the portion being removed, the waste will consist of successive shavings or chips, which may readily be disposed of through the suction-pipe 120. This will ordinarily comprise a considerable part of the margin, and what may be left at the toe will not be of sufficient length to become entangled with the operating elements but will drop freely from the guides and cutter. It will be seen that the edge 20 is called upon to do no work upon this transversely undivided portion.

With many types of shoe, the rounding operation may be completed in the above-described manner. If, however, as may be the case with prewelts, the crease at the forepart is uneven, when such a point is reached the operator depresses the rod 109 to swing down the lever 102. This causes the surface 106 to engage the roll 104, thereby turning the bell-crank-lever 98. The toggle formed by this lever and the link 92 is straightened, carrying down the slide 84 upon the crease-gage 50 and causing the surface 82 of the guide 80 to descend below the guide-portion 52 to receive contact of the comparatively smooth shoe-upper (Fig. 9). This continues until the shank-portion at the opposite side of the shoe is reached, when the rod 109 is released. The toggle is broken by the spring 102, and the crease-guide 50, 52 becomes again effective. The entire sole-edge produced will be close to the true contour, requiring little trimming. The operation with the high-speed cutter obviously may be performed at a very rapid rate. Because the action upon the work of the cutting edges 18 and 20 upon the spaced arms 16, 16 is separated by an interval in which the cutter is not acting, this gives a period during which the work is advanced by the operator and the belt 110 without encountering resistance caused by the presence of the cutter in the work. If a thicker portion of the sole-edge passes between the guides and the shear-blades, the spring 78 or the spring 113 will yield to compensate for the difference. When the cutter is to be removed for sharpening, or if for any reason access is desired to the operating elements, the hood 137 is swung back, the pin 72 in the guide-carrier 56 is withdrawn from the lever-opening 68, the carrier is raised, and the pin permitted to enter the opening 70 (Fig. 8). This positions the guides above and clear of the cutting mechanism.

In references made in the description and claims to the upper and the sole of a stitchdown shoe, it is to be understood that the upper is that portion above the crease and that the out-turned flange of upper-material becomes a part of the sole.

Having described my invention, what I claim as new and desire to secure by Letters Patent of the United States is:

- 10 1. In a sole-rounding machine, a rotatable cutter, and means arranged to engage a shoe-upper at points along the crease opposite the margin of an attached sole and being spaced from said upper outside the crease, such means being adapted to guide the sole in a direction generally parallel to the axis of the cutter and to present the sole to said cutter to be severed along an edge-surface substantially at right-angles to the opposite faces of the sole, the cutter being provided with spaced peripheral cutting edges entering the margin of the sole at the side toward the shoe-upper.
- 15 2. In a sole-rounding machine, a rotatable cutter, means arranged to guide a sole in a direction generally parallel to the axis of the cutter and to present the sole to said cutter to be severed along an edge-surface substantially at right-angles to the opposite faces of the sole, the cutter being provided with arms spaced from each other between which arms the sole may be advanced, said arms having peripheral cutting edges arranged to sever successive sections of the sole-margin, the arms also have cutting edges extending inwardly from the peripheral edges and arranged to divide the severed margin into separate chips.
- 20 3. In a sole-rounding machine, a rotatable cutter, means arranged to guide a sole in a direction generally parallel to the axis of the cutter and to present the sole to said cutter to be severed along an edge-surface substantially at right-angles to the opposite faces of the sole, the cutter being provided with arms spaced from each other between which arms the sole may be advanced, said arms having peripheral cutting edges arranged to sever successive sections of the sole-margin, the arms also have cutting edges extending inwardly from the peripheral edges and arranged to divide the severed margin into separate chips.
- 25 4. In a sole-rounding machine, a rotatable cutter, means arranged to guide a sole in a direction generally parallel to the axis of the cutter and to present the sole to said cutter to be severed along an edge-surface substantially at right-angles to the opposite faces of the sole, the cutter being provided with a peripheral cutting edge entering the margin of the sole at the side toward the shoe-upper and with a cutting edge extending inwardly from said peripheral edge, and two stationary blades with which the cutting edges respectively co-operate and against which the bottom margin of the sole rests.
- 30 5. In a sole-rounding machine, a rotatable cutter, means arranged to guide a sole in a direction generally parallel to the axis of the cutter and to present the sole to said cutter to be severed along an edge-surface substantially at right-angles to the opposite faces of the sole, the cutter being provided with a peripheral cutting edge entering the margin of the sole at the side toward the shoe-upper and with a cutting edge extending inwardly from said peripheral edge, and two stationary blades with which the cutting edges respectively co-operate and against which the bottom margin of the sole rests, and means arranged to vary independently the relation of the two blades to the co-operating cutter edges.
- 35 6. In a sole-rounding machine, a rotatable cutter, and means arranged to enter the crease of a shoe and to guide its sole in a direction generally parallel to the axis of the cutter and to present the sole to said cutter to be severed along an edge-surface substantially at right-angles to the opposite faces of the sole, said guiding means being yieldable under the influence of the work.
- 40 7. In a sole-rounding machine, a rotatable cutter, guiding means entering the crease of the

shoe adjacent to the cutter, and guiding means contacting with the shoe-upper adjacent to the cutter, said means being arranged to guide a sole in a direction generally parallel to the axis of the cutter and to present the sole to said cutter to be severed along an edge-surface substantially at right-angles to the opposite faces of said sole.

7. In a sole-rounding machine, a rotatable cutter, guiding means entering the crease of the shoe adjacent to the cutter, and guiding means contacting with the shoe-upper adjacent to the cutter, both guiding means being yieldable together under the influence of the work and being arranged to guide a sole in a direction generally parallel to the axis of the cutter and to present the sole to said cutter to be severed along an edge-surface substantially at right-angles to the opposite faces of said sole.

8. In a sole-rounding machine, a rotatable cutter, a guiding member entering the crease of a shoe adjacent to the cutter, a guiding member contacting with the shoe-upper adjacent to the cutter, said members being arranged to guide a sole in a direction generally parallel to the axis of the cutter and to present the sole to said cutter to be severed along an edge-surface substantially at right-angles to the opposite faces of said sole, and means whereby either member may be made effective.

9. In a sole-rounding machine, a rotatable cutter provided with a peripheral cutting edge entering the margin of the sole at the side toward the shoe-upper and a cutting edge extending at an angle from the peripheral edge, angularly related stationary blades with which the cutting edges co-operate and against which the bottom margin of the sole rests, and guiding means contacting with the shoe-upper adjacent to the cutter and stationary blades, said guiding means being arranged to guide a sole in a direction generally parallel to the axis of the cutter and to present the sole to said cutter to be severed along an edge-surface substantially at right-angles to the opposite faces of said sole.

10. In a sole-rounding machine, a rotatable cutter provided with a peripheral cutting edge entering the margin of the sole at the side toward the shoe-upper, a stationary blade with which the cutting edge co-operates and against which the bottom margin of the sole rests, and guiding means contacting with the shoe-upper adjacent to the cutter and stationary blade, said guiding means being yieldable from said stationary blade and being arranged to guide a sole in a direction generally parallel to the axis of the cutter and to present the sole to said cutter to be severed along an edge-surface substantially at right-angles to the opposite faces of the sole.

11. In a sole-rounding machine, a rotatable cutter provided with a peripheral cutting edge entering the margin of the sole at the side toward the shoe-upper, a stationary blade with which the cutting edge co-operates and against which the bottom margin of the sole rests, and plural guiding members for respective engagement with the crease and the upper of the shoe adjacent to the stationary blade, said members being arranged to guide a sole in a direction generally parallel to the axis of the cutter and to present the sole to said cutter to be severed along an edge-surface substantially at right-angles to the opposite faces of the sole.

12. In a rounding machine, a movable cutter, a movable shoe-guide co-operating therewith, a second shoe-guide carried by the first to move

thereon, and means arranged for actuation by the operator to move the second guide into and out of active position during the operation of the machine.

5. 13. In a rounding machine, a movable cutter, a movable shoe-guide co-operating therewith, a slide movable upon the guide, a second guide carried by the slide, a member acting upon the slide to move it upon the first guide, and a member connected to the first-named member and arranged for actuation by the operator.

10. 14. In a rounding machine, a movable cutter, a movable shoe-guide co-operating therewith, means arranged to move the guide, a second shoe-guide movable upon the first, and means arranged to move the second guide into and out of active position, the second moving means being without effect upon the positions of the guides during the action of the first moving means.

15. 15. In a rounding machine, a movable cutter, a movable shoe-guide co-operating therewith, means arranged to move the guide, a second shoe-guide carried upon the first to move thereon, and means arranged to move the second guide into and out of active position and comprising elements which may travel into and out of effective relation to each other.

20. 16. In a sole-rounding machine, a frame, a rotatable cutter journaled therein, a lever fulcrumed upon the frame, a crease-guide carried by the lever and co-operating with the cutter, an upper-guide movable upon the crease-guide, a lever fulcrumed upon the crease-guide-lever and connected to the upper-guide, and means arranged to oscillate the upper-guide-lever.

25. 17. In a sole-rounding machine, a frame, a rotatable cutter journaled therein, a lever fulcrumed upon the frame, a crease-guide carried by the lever and co-operating with the cutter, a slide movable upon the crease-guide, an upper-guide mounted upon the slide, a toggle-lever carried by the crease-guide-lever and connected to the slide, and a lever fulcrumed upon the frame and movable against a portion of the toggle-lever.

30. 18. In a sole-rounding machine, a frame, a rotatable cutter journaled therein, a lever fulcrumed upon the frame, a crease-guide carried by the lever and co-operating with the cutter, a slide movable upon the crease-guide, an upper-guide mounted upon the slide, a toggle-lever carried by the crease-guide-lever and connected to the slide, a spring holding the toggle normally broken and the upper-guide in an inactive position, and a lever fulcrumed upon the frame and movable against a portion of the toggle-lever to move the upper-guide to an active position.

35. 19. In a sole-rounding machine, a frame, a rotatable cutter journaled therein, a lever fulcrumed upon the frame, a crease-guide carried by the lever and co-operating with the cutter, a slide movable upon the crease-guide, an upper-guide mounted upon the slide, a toggle-lever carried by the crease-guide-lever and connected to the slide, means arranged to vary the point of attachment of the toggle-lever to the slide, and a lever fulcrumed upon the frame and movable against a portion of the toggle-lever.

40. 20. In a sole-rounding machine, a frame, a rotatable cutter journaled therein, a lever fulcrumed upon the frame, a carrier variable in position upon the lever, a shoe-guide mounted upon the carrier and co-operating with the cutter, and means arranged to secure the carrier

upon the lever with the guide differently located with respect to the cutter.

21. In a sole-rounding machine, a frame, a rotatable cutter journaled therein, a lever fulcrumed upon the frame, a carrier pivoted upon the lever, means for securing the carrier in different angular relations upon the lever, and a crease-guide mounted upon the carrier and co-operating with the cutter.

22. In a sole-rounding machine, a frame, a rotatable cutter journaled therein, a lever fulcrumed upon the frame, a carrier pivoted upon the lever, means for securing the carrier in different angular relations upon the lever, a crease-guide mounted upon the carrier and co-operating with the cutter, and means arranged to fix the crease-guide in different positions upon the carrier.

23. In a rounding machine for shoe-soles, a cutter movable against one side of a sole, a rotatable feed member engaging the opposite side of the sole, means for rotating the feed member, and a guide engaged by the shoe in a plane between the approaching cutter and feed member.

24. In a sole-rounding machine, a cutter movable against one side of a sole, a belt engaging the opposite side of the sole, means for driving the belt, and a shoe-guide co-operating with the cutter and belt.

25. In a rounding machine, a rotatable cutter, a plurality of rotatable supporting members, means for driving one of the supporting members, and an endless work-feeding member running over the supporting members and arranged to be engaged by and advance a shoe held in

the hands of the operator to receive the rounding action of the cutter.

26. In a rounding machine, a rotatable rounding cutter, a guide situated adjacent thereto for engagement with a shoe at the crease, a rotatable feed member engaging the shoe-bottom below the cutter and guide, and means for rotating the member.

27. In a rounding machine, a rotatable cutter, a work-guide situated adjacent thereto, a rotatable feed member engaging the work below the cutter and guide, means for rotating the member, a rest for the work below the feed member, and means arranged to vary the position of the rest inwardly or outwardly with respect to the work-engaging surface of said feed member.

28. In a rounding machine, a rotatable cutter, a shear-blade co-operating therewith, a rotatable work-feeding member, a tubular shaft by which the member is carried, and a support for the shear-blade extending through the shaft.

29. In a rounding machine, a rotatable cutter, a shear-blade co-operating therewith, a pulley having a tubular shaft, a feed-belt running upon the pulley, and a support for the shear-blade extending through the shaft.

30. In a rounding machine, a rotatable cutter, a shear-blade co-operating therewith, a pulley having a tubular shaft, a feed-belt running upon the pulley, a support for the shear-blade extending through the shaft, and means arranged to raise and lower the support.

JOHN M. WHELTON.
